(57) **CLAIM**

The ornamental design of a handgun grip insert, as shown and described.

DESCRIPTION

FIG. 1 is a perspective view of a handgun grip insert showing my design;

FIG. 2 is a front elevational view thereof;

FIG. 3 is a right-side elevational view thereof, the left-side being a mirror-image thereof;

FIG. 4 is a rear elevational view thereof;

FIG. 5 is a top plan view thereof;

FIG. 6 is a bottom plan view thereof;

FIG. 7 is a right-side elevational view of an alternative embodiment of the handgun grip insert of FIG. 1, the left-side being a mirror-image thereof; and,

FIG. 8 is a right-side elevational view of another alternative embodiment of the handgun grip insert of FIG. 1, the left-side being a mirror-image thereof.
